(57) **CLAIM**

The ornamental design for a spray nozzle, as shown and described.

DESCRIPTION

FIG. 1 is a perspective view taken from the front, top, and right side of the ornamental design for a spray nozzle.

FIG. 2 is a front elevation view of the spray nozzle of FIG. 1.

FIG. 3 is a rear elevation view of the spray nozzle of FIG. 1.

FIG. 4 is a right side elevation view of the spray nozzle of FIG. 1.

FIG. 5 is a left side elevation view of the spray nozzle of FIG. 1.

FIG. 6 is a top plan view of the spray nozzle of FIG. 1; and, FIG. 7 is a bottom plan view of the spray nozzle of FIG. 1. Features of the spray nozzle shown in evenly spaced broken lines form no part of the claimed design. The broken dot-dash-dot line in FIG. 7 indicates an outer boundary of an unclaimed region and forms no part of the claimed design.

1 Claim, 7 Drawing Sheets
